WALL CONSTRUCTION

Percy E. Knudsen, Pittsburgh, and John A. Desmone, Springdale, Pa., assignors to Pittsburgh Corning Corporation, a corporation of Pennsylvania

Application October 31, 1940, Serial No. 363,610

2 Claims. (Cl. 72—106)

The present invention relates to panel constructions for an opening in a building wall and it has particular relation to the provision of a filler between a margin of such opening and a margin of a panel of glass blocks disposed in the opening.

One object of the invention is to provide a filler of the foregoing type which is attractive in appearance, simple and inexpensive to manufacture, which will permit movements, such as expansion and contraction or distortion between the margins of the panel and the margins of the opening without imposing strain upon the blocks constituting the panel and will, at the same time, support the panel against thrusts exerted against the face thereof.

This and other objects of the invention will be apparent from consideration of the following specification and the appended claims.

It has heretofore been proposed to construct panels of hollow blocks of glass as fillers for openings in a building wall. Such blocks are attractive in appearance, function as light-transmitting media, and because of their hollow construction are relatively highly resistant to the transmission of heat. The blocks, because of their hollow construction, are not designed to act as load-carrying elements for the wall above. Therefore, if the panel is relatively wide, i. e. constitutes within itself a main part or a large portion of a building wall, a lintel structure of suitable strength is required in order to support walls or floors or roof superposed thereupon. The lintels inherently tend to sag and they as well as the panels are subject to thermal expansion and contraction as well as movements due to settling or distortion of the building in which they are disposed. For these reasons, as well as for purposes of facilitating the assembly of the panels, it is desirable to leave a substantial space between the upper edge of the panel and the lintel thereabove.

The present invention contemplates the provision of a filling between the upper edge of a panel of glass blocks and the lower face of a lintel structure, which filling includes, among other features, an anchor element designed to resist thrust against the face of the wall, and also being vertically slidably in suitable guides to permit relative vertical movement of the upper edge of the panel.

For a better understanding of the invention reference may now be had to the accompanying drawings in which like numerals refer to like parts throughout.

In the drawings

Figure 1 is a fragmentary elevational view of a portion of a wall embodying the principles of the present invention;

Figures 2, 3 and 4 are fragmentary sectional views taken respectively upon the lines II—II, III—III and IV—IV of Figure 1;

Figure 5, 6, 7 and 8 are fragmentary sectional views showing additional forms of the invention;

Figure 9 is a fragmentary sectional view taken substantially upon the line IX—IX of Figure 8.

In a wall constructed as shown in the drawings a panel 10 of conventional hollow glass building blocks is assembled by methods well understood in the art in an opening in a building wall 11. The blocks indicated at 12, (see Fig. 2) preferably include shoulder portions 13 providing a groove for the reception of mortar or other filling between contiguous blocks.

A sill structure for the panel indicated at 14 is shown in Figure 4, and includes a base portion 16, which may be a portion of the masonry of the wall. Shearlock bar 17 is disposed thereupon and may be held in place by suitable lag screws or bolts 18. The bar or sill shall be coated with a layer of non-adhesive material 19, such as asphalt, emulsion covered with impregnated roofing paper or building paper, which layer in turn is covered by a layer 21 of mortar, which fills the space between the shoulders 13 of the contiguous building blocks 12. A caulking 22 of plastic and relatively moistureproof material disposed between the lower edge of the outer shoulder and the upper face of the sill portion 16 provides a seal to prevent permeation of the mortar by moisture.

A jamb structure for the panel is shown in Figure 3 and includes vertical portions 23 of the margin of the wall contiguous to the open panel. A shoulder 26 formed in the portion 23 provides an abutment back of the vertical edges of the blocks, in order more securely to anchor the edges of the panel in place. The space between the jamb portions of the wall and the contiguous edges of the block preferably is provided with a resilient packing 27 which may comprise a layer of cork, felt or the like, which will permit relative expansion and contraction of the block panel without imposing a strain upon the blocks themselves. This packing of resilient material is sealed from the external atmosphere by means of a resilient and waterproof caulking 28 of conventional caulking compound. The sill and jamb structures above described may be employed in

combination with any of the filler structures to be described.

A lintel construction embodying a filler between the upper edge of the panel and the edge of the opening in the wall is shown in Figure 2 and includes an angle bar 29 having flanges 31 and 32, which engage and support the masonry 33 above the panel.

Preferably layer 34 of mortar or cement is disposed between the lower face of the masonry and the upper face of the flange 31 of the angle. To the branch 32 of the angle is secured a vertical member 36 which may constitute one leg or branch of a second angle member 37, having a horizontal leg or branch 38. The element 36 preferably extends slightly below the upper edge of the glass block panel and may be provided with a facing 39.

A small angle element 41, secured to the angle 37 by means of bolts or rivets 42, is provided with a vertical flange or leg 43, which is disposed in slightly spaced relation with respect to the inner face of the member 32, to provide a channel or guideway, and thus provides an anchorage for maintaining the upper edge of the panel against thrusts exerted against the face thereof. A thin layer 44 of mortar or cement is disposed in the channel upon the upper edge of the panel 10 provided by the peripheral grooves in the upper course of blocks and is covered by a plate 46 having a downwardly-projecting flange 47 disposed between leg 43 of angle element 41 and bar 36.

Anchor straps 50 are secured by appropriate means to bars 46 and are embedded in the mortar between the blocks to prevent displacement of the panel. These anchors are also duplicated in the structures shown in 5, 6, 7 and 8 and are there designated by a like numeral.

Upon the top of the plate is disposed a packing 48 of mineral wool, fibered glass, felt or other material designed to fill the space between the edge of the panel, the upper face of the bar 21. This packing is faced by an extensible pleated sheet 49, of roofing paper or similar material having a foil-like covering of copper or other resilient material. The upper edge of this extensible sheet element may be secured by embedding a flap 51 thereof in the layer 34 of cement. The lower margin preferably is bent upwardly as indicated at 52 and is then bent over as indicated at 53 to engage a vertical flange 54 upon the plate 46. The pressure of the mineral wool upon the portion 53 prevents its displacement from the flange.

A further form of the invention as shown in Figure 5 involves a panel 60 of glass blocks essentially corresponding to the panel 10, which panel is disposed in an opening in a building wall 61. Contiguous to the wall may be disposed a beam 61a and mortar 61b may fill the joint. An extensible element for filling the space between the edge of the panel and corresponding edge, e. g. the jamb or the lintel portions of the opening, and for anchoring the edge of the panel against thrusts, may include a channel-like member 62 disposed in the space between wall 61 and beam 61a or embedded or otherwise secured in the contiguous portion of the opening in the building, and being provided with a spring clip element 63 disposed therein. The latter is of inverted channel-like section and preferably includes side portions 64, which are inwardly bowed in order resiliently to press against a metallic flange 66, which is laterally directed with respect to the edge of the panel.

Flange 66 is integral with a bar-like plate 68 resting upon a layer 71 of cement disposed between the shoulders of the blocks constituting the panel. A layer 72 of loosely packed oakum or other relatively yieldable material is packed between the plate and the contiguous surface 73 of the opening in the building wall and admits of expansion and contraction of the panel without imposing strains thereupon. Shoulder 74 is also formed about the margin of the opening and a packing 76 of caulking material is disposed between the shoulder and the adjacent marginal portion of the face of the panel 60. Further a compressible and expansible packing 77 is provided between the opposite shoulders of the blocks constituting the panel and the face 73 of the opening, in order completely to seal the packing 72.

It will be apparent that any relative movement 20 between the marginal portions of the panel 60 and the edges of the wall 61 causes the flange 66 to slide between the walls of the clip 63 without in any way stressing the panel 60. At the same 25 time, the channel-like clip 63 provides an effective seal about the flange.

The form of the invention shown in Figure 6 is particularly designed to provide an extensible seal and anchorage between the vertical or jamb margins of a panel and contiguous portions of a building wall. However, it will be apparent that it is also adapted for forming a seal between the upper edge of the panel and the adjacent lintel portion of the opening in which the panel is disposed. This construction includes a channel 80 30 of U section, which is embedded in the contiguous portions of a building and which slidably receives a flange 81 upon a plate 82 bearing upon a layer 83 of cement or the like upon the margins 35 of the panel.

A mullion structure for use between a pair of panels embodying the invention illustrated in this figure or other figures is, also, shown and includes a bar 86 similar to the bar 82 and resting against a packing 87 of cement or the like. Bar 86 has a laterally directed flange 88 disposed in the space between one leg 89 of an angle bar 91 and the head portion 92 of a T iron 93. The second leg 94 of angle 91 may be secured by bolts or rivets 95 to the web portion 96 of the T iron, 45 which may be embedded in concrete column 97. The face of the head portion 92 is covered with a resilient sheet material 98 which may comprise a layer of felt having a thin flexible covering of copper, aluminum or other suitable relatively 50 flexible metal. The marginal portions of the sheet are crimped as indicated at 99, along a line parallel to the direction of extension of the mullion in order to give a certain degree of extensibility thereto. The flap 101 of the marginal portion is doubled over the inner face of the bar 86 and is embedded in the outer portion of the cement layer 87. It will be apparent that the joint between the mullion and the panel 103 upon the opposite side of the mullion corresponds to that described.

A modification suitable for use between the jamb or the head of a panel and adjacent portions of the building is shown in Figure 7. This construction includes a bar 105 of aluminum, bronze or the like resting upon a layer 106 of cement upon the edge of a glass block panel 107. The bar is provided with a downwardly bent shoulder or lip 108, which is designed to provide a drip element and which is integral 70 with an upwardly-extending flange 109. The

latter is slidably disposed between vertical legs 111 and 112 of angle irons 113 and 114. Horizontal legs 116 and 117 of the angle irons are superposed upon each other and are held together by bolts 118, which may extend into adjacent portion 119 of the building.

In the form of the invention disclosed in Figure 8, an angle beam 125 constituting a lintel in an opening in a building wall is supported in any convenient manner, for example by means of columns or pillars (not shown) at its ends and/or by bolts 126 extending through vertical flange 121 of the iron into a beam or like support. The horizontal flange 128 of the beam supports the wall 129 of any convenient material. Below the flange 128 is disposed panel 131 of glass blocks, which may have a layer 132 of mortar or the like disposed thereupon. Upon the latter is disposed horizontal flange 133 of an angle element 134 having a vertical flange 136. The vertical flange is slotted as indicated at 137 to receive bolts 138 extending through flange 127. Washers 139 upon the bolts engage opposite sides of flange 136 and act as guides to permit slight relatively vertical movement between beam 125 and the flange 133. Between the washers 139 is disposed a washer 140 of slightly greater thickness than flange 136. It is of such diameter as to fit within slot or notch 137, and assures that washers 139 will not be drawn so close together as to clamp or bind the flange.

A yieldable filler layer 141 of cork or the like seals the space between the flanges, but does not substantially oppose the movement. The edges of the cork and of the layer 132 are sealed by packing 142 of yieldable but waterproof caulking material.

Flashing 143 of thin flexible metal covers the faces of flanges 127 and 128 and a lip portion 144 is bent down over the edge of the latter flange to provide protection and also to give a pleasing finish. Flanges 47, 68, 81, 88, 109 and 136 all lie as shown in the drawings in a plane contiguous to or adjacent to a face of the corresponding panel.

What we claim is:

1. A building construction comprising a wall having an opening formed therein, the portion of the wall above and contiguous to the opening constituting a lintel for the opening, a panel comprising glass blocks with peripheral grooves for receiving mortar laid in edge to edge relation with respect to each other in the opening, and the grooves in the upper course of blocks providing a channel along the upper edge of the panel, the upper edge of the panel being spaced from the lintel, an angle bar cemented to the top edge of the panel by mortar embedded in said channel, said bar being provided with an upwardly turned flange contiguous to the plane of one face of the panel and guide means secured to said lintel and slidably engaging the face of the flange to maintain the panel from displacement by forces exerted vertically thereto, but permitting relative movement of the panel in its own plane without substantial strain.
2. A building construction comprising a wall including a plurality of transversely spaced panels composed of glass blocks laid in edge to edge relation, a mullion disposed between two of the panels and comprising a vertically disposed metallic bar having oppositely disposed transverse flanges along one edge, angle bars secured to the first-mentioned bar and having flanges parallel to but spaced slightly from the first-mentioned flanges, to provide guide slots, angle bars secured upon the adjacent edges of the panels and having flanges disposed slidably in the guide slots, whereby to constrain the panels from movement in a direction perpendicular to the plane thereof, but permitting relative movement of the panels in their own plane with respect to the mullion, a flexible cover sheet of metal having the marginal portions thereof disposed between the edges of the panels and the second-mentioned angle bars and being formed with flexures parallel to the bar, admitting of relative movement between the panels and the mullions without imposition of substantial strain upon the panels.

JOHN A. DESMOND.
PERCY E. KNUDSEN.
